UNITED STATES PATENT OFFICE.

JESSE B. GARBER, OF SALEM, OHIO, ASSIGNOR TO THE DEMING COMPANY, OF SALEM, OHIO, A CORPORATION OF OHIO.

PUMP.

Application filed February 13, 1926. Serial No. 88,005.

This invention is directed to improvements in piston pumps. Such pumps usually embody check valves disposed at the inlet and outlet ports thereof which are respectively responsive to suction and pressure upon the operation of the piston. Such valves usually entail the embodiment of a number of accurately machined parts in the pump, eventually resulting in an inefficient operation of the pump due to wear. The ingress of extraneous matter carried into the pump by the fluid passing therethrough also frequently interferes with the accurate seating of the valve members.

The general object of my invention therefore is the provision of a valve mechanism in the form of a simple unitary structure, which in my present embodiment is illustrated as being particularly adaptable for use in oscillating piston pumps and which mechanism is of such character as to eliminate the use of the usual check or poppet valve members.

A further object of my invention is the provision of an oscillating pump embodying a minimum number of parts, economically formed, which will efficiently function irrespective of the presence of extraneous solid matter in the fluid passing through the pump.

A still further object of my invention is the provision of a simple valve mechanism for a pump of the character referred to which may comprise a single member for controlling the pump inlet and outlet ports.

Other objects of my invention will hereinafter be set forth in the following description referring to the accompanying drawings illustrating a preferred form thereof. The essential characteristics are summarized in the claims.

In the drawings, Fig. 1 is a perspective view of an oscillating piston pump embodying the features of my invention. Fig. 2 is a perspective view of a member comprising all of the valve mechanism of the pump. Fig. 3 is a perspective view of the pump piston. Fig. 4 is a cross-sectional elevation taken through the center of the pump. Fig. 5 is a cross-sectional view taken substantially along the line 5—5 of Fig. 4. Fig. 6 is a cross-sectional view similar to the view shown in Fig. 5 but illustrating a shifted position of the valve mechanism. Fig. 7 is a cross-sectional view similar to the view

shown in Fig. 6 but showing a different position of the piston and Fig. 8 is a side elevation of the piston.

Oscillating piston pumps usually comprise a casing having a cylindrical bore adapted for the reception of an oscillating piston in the form of two oppositely extending radial arms, the ends of which contact with the cylindrical bore of the casing and some form of partitioning means is provided to divide the interior or casing into a separate compartment for each arm of the piston. Such partitioning means has heretofore comprised valve decks or valve carrying members with at least two valve members operatively attached to each deck.

My invention contemplates the use of a simple valve mechanism which may also comprise the casing partitioning means and in Figs. 4 and 5, I show the pump as comprising the usual casing 10 having a suitable bore for receiving the oscillating piston 11 and a partitioning means in the form of an oscillating valve member 12. The piston is provided with a shaft 14 and the casing is suitably formed at one end as shown at 15 to afford a bearing for properly supporting the piston shaft 14. A stuffing box gland 16, packing sleeve 17 and a nut 18 carried by the casing serve to pack the shaft 14. An operating handle 20 is shown in Fig. 4, mounted on an extension of the shaft 14 and operating the piston 11. The opposite end of the casing may be sealed by a closure disk 22, having formed at its center a cup-shaped portion 24 to receive a spring member 25 at its inner end, bearing against the valve member 12 to urge the latter member into contact with the end of the piston and an end wall of the casing as will be hereinafter described. The closure member 22 may be secured to the casing by any suitable means such as bolt members, indicated at 30 in Fig. 6.

The casing may be provided with an upper threaded branch 9 in communication with the interior of the casing through an outlet port 10^b and a lower threaded branch 9^a in communication with the interior of the casing through two spaced apart inlet ports 10^a. These ports are controlled by an oscillating movement of the valve member 12 as will be hereinafter set forth.

The hub of the piston 11 is preferably formed hollow with two independent passageways 34 and 35 extending therethrough.

- These passageways extend in a criss cross manner through two oppositely disposed radially extending flat arms 11^a and 11^b. These arms contact at the ends thereof with the bore of the casing and oscillate in compartments 31 and 32, which are formed within the pump casing by the peculiar construction of the valve member 12. The sides of the arms are accurately formed to contact with the end walls of the compartments and the passageways serve to establish communication between the two compression sides and the suction sides of the piston arms when the piston is oscillated.
- 15 The hub surface of the piston is preferably concentrically formed to accurately fit the valve member 12 whereby leakage between the casing compartments is prevented and the valve member, as shown in Fig. 2, may comprise in detail, a disk portion 40 of sufficient diameter to accurately fit the bore of the casing and upon this disk 40, I prefer to integrally form casing partitioning walls 41 and 42. These walls may be of such shape that radial ends thereof will overlie or be disposed at either side by the outlet port 10^b and the pair of inlet ports 10^a and the wall 41 is accordingly of such shape as will provide two inlet passageways 41^a. When the disk member 40 is rocked or oscillated within the pump casing, one of its passageways is alternately brought into registration with one of the inlet ports 10^a and a portion 42^b of the wall 42 is alternately shifted to be disposed to one or the other side of the outlet port 10^b. The wall 42 is undercut annularly, as shown at 45, whereby communication may be established between the outlet port 10^b and either one of the compartments 31 and 32. The inner radial ends of the partition walls 41 and 42 are concentrically formed relative to the center of the disk 40 to accurately fit the concentric portion of the piston hub, as stated, whereby leakage from one compartment to the other of the pump is prevented. It will thus be seen that when the pump piston is oscillated, pressure is brought to bear on the liquid present in the compartment in alternate annular directions thus causing the disk member to oscillate within the pump casing and I provide means for limiting this oscillating movement of the valve member 12 relative to the piston movements which may comprise a pin or screw member 46 (see Fig. 4), extending inwardly from an end wall of the casing into a cavity 42^c formed in the wall 42 of the disk member 40.
- 60 The width of the walls 41 and 42 is accurately defined to equal the width of the pump arms 11^a and 11^b whereby the action of the spring 25 upon the valve member will urge the disk portion of the latter against the end of the piston and the wall 65 portions 41 and 42 against the inner end wall of the casing thus preventing undue leakage of the fluid between the valve members, the piston and the casing as the piston and valve member are oscillated. The operation of the pump is as follows:
- Assuming the piston to be in the position shown in Fig. 5, with the arm 11^a in its maximum upward position and the valve member shifted to the right to a maximum position determined by the stop pin 46; then upon a reverse movement of the piston, the arm 11^b thereof will start upwardly and the arm 11^a downwardly and fluid present in the compartment 31 on the under side of the arm 11^a will become compressed. Part of this fluid will escape through the passage 25 but sufficient pressure will be exerted upon the wall 41 of the valve member to cause it to be shifted to the position shown in Fig. 6, thus exposing the outlet port 10^b to the compartment 32 and causing the right-hand inlet passageway 41^a of the valve member to register with the inlet port 10^a. The arm 11^b will thus draw the fluid into the chamber 32 through the right-hand port 10^a and force the fluid coming from the compartment 31 through the outlet port 10^b during its upward movement. When the movement of the arm 11^b after it has reached its maximum upward movement, is reversed, the cycle of pumping actions is repeated in the compartment 31 by the arm 11^a.
- It will be evident from the foregoing description of the embodiment of my invention herein illustrated that only two moving parts are embodied in the pump—the oscillating piston and the oscillating valve member and the form of these two members may be such that they may readily and accurately be manufactured in an economical manner to operate in a casing of simple design.
- Having thus described my invention, I claim:
1. In a pump, the combination of a casing having an inlet and an outlet, a piston disposed within the casing, an oscillating valve means for alternately opening and closing said inlet and outlet, said valve means having a disc-like portion extending across the end of the piston, and means for urging the piston and valve means into endwise contact.
  2. In a pump, the combination of a casing having an inlet and an outlet, valve means oscillatingly disposed within the casing, said valve means forming two chambers within the casing, an oscillating piston extending into said chambers, said piston having two passageways extending therethrough and establishing communication between the chambers, means for oscillating the piston and means for pressing the valve means constantly against the end of the piston.
  3. In a pump of the character described, the combination of a casing having an inlet

- and an outlet, an oscillating piston within the casing, an oscillating valve means disposed within the casing to control said inlet and outlet upon an oscillating movement 5 of the piston, said valve means comprising means for dividing the interior of the casing into two compartments and having a disc portion contacting with the end of the piston, said casing having a cylindrical bore, 10 said valve means and the ends of the piston being formed to contact with said bore, and the straight ends of the piston rubbing against the disc portion.
4. In a pump of the character described, 15 the combination of a casing having an inlet and an outlet, an oscillating piston disposed within the casing, said casing having a cylindrical bore in contact with the ends of the piston, an oscillating valve member con- 20 tacting with a hub of the piston, and forming compression chambers within the casing
- said valve means being operative to alternately open and close said outlet and inlet of the casing, the valve means including a disc portion contacting with the piston and 25 an outer casing closure member inclosing the valve member and piston, and a spring shoving the valve member toward the piston.
5. In a pump, the combination of a cas- 30 ing having an inlet and an outlet, two valve members respectively connecting the inlet and outlet, a disc carrying the valve mem- bers, an oscillating piston having a pair of wings, one lying at the left of one valve 35 member, and the other at the right of the other valve member, the end of said piston rubbing against said disc, and a spring pushing the disc against the piston.

In testimony whereof, I hereunto affix 40 my signature.

JESSE B. GARBER.
